DESIGN FOR A SUIT

Louise Barnes Gallagher, New York, N. Y.

Application July 19, 1941, Serial No. 102,228

Term of patent 3½ years

To all whom it may concern:

Be it known that I, Louise Barnes Gallagher, a citizen of the United States, residing in New York city, in the county of New York and State of New York, have invented a new, original and ornamental Design for a Suit of which the following is a specification, reference being had to the accompanying drawing, forming part thereof.

I claim:

The ornamental design for a suit, substantially as shown.

LOUISE BARNES GALLAGHER.
